UNITED STATES PATENT OFFICE.

JOHN R. FLINN, OF JOHNSTOWN, PENNSYLVANIA.

DEPOSIT AND COLLECTION RECEPTACLE.

1,231,724.

Specification of Letters Patent.

Patented July 3, 1917.

Application filed October 25, 1916. Serial No. 127,558.

To all whom it may concern:

Be it known that JOHN R. FLINN, a citizen of the United States, residing at Johnstown, in the county of Cambria and State of Pennsylvania, has invented certain new and useful Improvements in Deposit and Collection Receptacles, of which the following is a specification.

This invention relates to deposit and collection receptacles.

This invention has for an object to provide a container or receptacle adapted to be placed in convenient proximity to the door, and to receive milk bottles, or the like, to house the same from the elements and prevent access thereto or casual displacement thereof by dogs or cats, but to permit access thereto by authorized persons.

Another object of the invention is to provide a container with a top having an opening therein through which a bottle may be placed, and to equip the container with a cover which may be placed and locked over the opening to prevent access to the bottle in the container.

The invention has for a further object to provide a container to which access may be gained through a side and the top, and to equip the container with internal means operable by the weight of the bottle to coact with a closure to positively prevent communication to the interior of the container through said top.

The above, and other objects and advantages of this invention will be more particularly brought out in the following detailed description of the present preferred embodiment, the same being illustrated in the accompanying drawings, wherein:

40 Figure 1 is a perspective view of a deposit and collection receptacle constructed according to the present invention, and applied to a suitable support adjacent a door, showing the cover in an open position.

45 Fig. 2 is a longitudinal sectional view of the container, a milk bottle being shown therein, in dotted lines.

50 Fig. 3 is a front elevational view of the device, showing the door in open position, parts of the container being broken away to disclose details.

55 Fig. 4 is a detail fragmentary top plan view of the container, showing the cover removed therefrom.

Fig. 5 is a perspective view of the supporting platform used in this invention, and

Fig. 6 is a detail fragmentary perspective view of the latch mechanism.

In the drawings, in order to illustrate the application of the invention, a portion of a door and door casing 1 are shown, the latter having a bracket 2 associated therewith upon which my improved container, generally designated 3, is mounted. Although I have in this instance shown the container mounted upon the bracket or shelf 2 it is nevertheless to be understood that the container may be supported in any other desired way, and at any desired place.

The container 3 is in this instance shown to be of an oblong configuration and is preferably made of sheet metal, although any other suitable material may be used. One of the walls of the container is removed and the margin turned inwardly at right angles to provide a flange 4. A door 5 is hingedly mounted on one side of the container, at the jointure of the flange and the body of the container, and is equipped on its inner face with a lock 6, the sliding bolt of which is engageable beneath the flange 4 when it is desired to lock the door 5.

An opening 7 is formed in the top of the container and is shown to be of a size sufficiently large to accommodate a milk bottle, although the size, or number of openings in the top may be varied, to accord with the magnitude of the container, and the number of bottles, or other articles which are desired to be housed. To close communication through the opening 7 a cover or lid 8 is hinged on the top of the container at one side, the opposite side of the container being engaged by a right angle flange 9, which depends from the cover. A knob 10 is mounted in the cover 8 for convenience in operating the latter.

Arranged within the container is an article supporting structure, consisting of a platform 11, a portion of the front margin of which is bent downwardly at right angles to provide a supporting leg 12. Parallelly arranged ears 13 are bent upwardly from the lateral margins of the platform at a point intermediate the rear margin of the platform and the transverse center. The ears 13 are pivotally mounted on studs 14, the latter being carried by straps 15. The straps 15 are secured to the lateral walls of the container in proximity to the lower end of the latter, and have the free terminals thereof appreciably spaced from the con-

tainer to avoid contact of said ears 13, with the container. The rear margin of the platform is equipped with an upstanding finger 16, which is pivotally engaged with one end 5 of a link 17. As will be noted, the leg 12 limits movement of the platform 11 and also serves in the capacity of a means for holding the platform in an inclined position, as shown in Fig. 2 of the drawings, in order 10 to prevent the article carried by the platform, from accidentally falling out of the container when the door 5 is opened.

The upper terminal of the link 17 is pivotally engaged with a weight member 18, the latter being movable on an axis 19. Downward movement of the weight 18 is limited by an abutment 20, which is carried by the rear wall of the container. One terminal of the weight 18 is inclined and has a portion 20 projecting therefrom at its vertex, to provide a lug or finger 21. The finger 21 is engaged in the bifurcated end 22 of a latch member 23, the latter being pivoted approximately midway its ends and being movable 25 across an opening 25 formed in the top of the container. As shown to advantage in Fig. 3, the latch member 23 is adapted to co-operate with the corresponding member 24 on the cover 8.

30 A guard member 25^a is engaged with the opposite lateral walls of the container and is disposed at an inclination across the container, directly in front of the lower end of the link 17, and the upper end of the finger 35 16. The guard member will of course prevent interference of an article with the link member 17 and the finger 16.

In use of this device I will assume that the door 5 is closed and in a locked position, and 40 that the cover 8 is in an open position. An article may then be deposited in the container through the top opening 7. The weight of the article on the platform 11 will force the latter downwardly into a position 45 as shown in Fig. 2, in which position the latch member 23 will be arranged across the opening 25 in the top of the container. The person depositing the article may then urge the cover 8 into snug engagement with the 50 top of the container, thereby causing the

locking member 24 to be engaged with the latch member 23. When it is desired to remove the contents of the container, the lock 6 is opened by means of a suitable key and the door 5 then swung out in the usual way. 55 When it is desired to leave articles, such as empty milk bottles in the container for collection, the said articles may be placed on the platform 11, after which the door 5 is closed and locked, and the lid 8 moved into 60 close proximity to the top of the container to protect the article from the elements, but at the same time not locking the lid, to permit access to the container through the opening 7, for removing the empty milk bottle or 65 the like.

It is of course understood that changes and modifications may be made in the above specifically described embodiment of this invention, without departing from the spirit 70 thereof, and being restricted only by the scope of the following claims.

What is claimed is:

1. A deposit and collection receptacle including a container provided with top and 75 side openings and equipped with a cover to close said top opening, an article supporting platform arranged in the container and movable under pressure of the article, means actuated by the platform to lock the cover 80 when the latter is urged into engagement with the top of the container, and means to limit downward movement of said platform, said means also inclining the platform substantially as set forth. 85

2. A milk bottle holder including a container provided with an opening in its top and an opening in its side, a closure for said top opening, a platform mounted in the container to receive the bottle, means operatively connected with the platform for locking the closure under pressure of the bottle, means to incline the platform to prevent casual displacement of the bottle through said side opening, and a guard member 90 mounted in the container to prevent contact of the bottle with the locking means. 95

In testimony whereof I affix my signature.

JOHN R. FLINN.
